UNITED STATES PATENT OFFICE

160,288

RANGE

George F. Wales, Kenmore, N. Y.

Application September 15, 1948, Serial No. 148,596

Term of patent 14 years

(CL. D81—4)

To all whom it may concern:

Be it known that I, George F. Wales, a citizen of the United States, resident of Kenmore, in the county of Erie and State of New York, have invented a new, original, and ornamental Design for a Range, of which the following is a specification, reference being had to the accompanying drawings, forming a part thereof. This is a continuation-in-part of applicant's copending application Serial No. D. 127,812, filed March 22, 1946, now abandoned.

In the drawings:

Fig. 1 is a perspective view of a range embodying my new design with the front door in closed position;

Fig. 2 is a side view slightly in perspective, on a reduced scale and with the front door in its lowered and slideable disappearing position;

Fig. 3 is a front elevation of the range as shown in Fig. 1;

Fig. 4 is a sectional view taken on line 4—4 of Fig. 3 looking in the direction of the arrows; and

Fig. 5 is a front elevation of the range as shown in Fig. 2.

The dominant features of my design reside in the portions shown in full lines.

I claim:

The ornamental design for a range, substantially as shown and described.

GEORGE F. WALES.
